UNITED STATES PATENT OFFICE.

HARRY W. PINKERTON, OF RANDOLPH, MASSACHUSETTS.

SHOE-LACING.

SPECIFICATION forming part of Letters Patent No. 749,904, dated January 19, 1904.

Application filed May 11, 1903. Serial No. 156,579. (No model.)

To all whom it may concern:

Be it known that I, HARRY W. PINKERTON, residing at Randolph, county of Norfolk, and State of Massachusetts, have invented a new and useful Shoe-Lacing, of which the following is a specification.

My invention relates to improvements in shoe-lacings, and is applicable to the well-known form of lace-shoes in which a lacing 10 passing through a series of eyelets in each of the opposing edges of the front part of the upper serves to retain the shoe on the foot of the wearer. In this class of footwear after the laces have been drawn taut to "brace" the 15 shoe on the foot the ends of the laces are secured by a knot. A common form of knot employed is that known as the "single" knot supplemented by that known as the "double-bow" knot. The knot has been heretofore an 20 objectionable feature, both with regard to the time and patience required in tying and untying it and with regard to its unsightly appearance, for the necessary tension upon the knot has had a tendency to give a reduced size 25 and strained appearance to the bow.

It is the purpose of my present invention to provide an easy and rapid method of clasping or fastening together the two ends of the lacing and at the same time to admit of a bow or 30 other ornamental knot of any desired form or character.

My invention consists of a shoe-lacing, near one end of which is secured a clasp or fastening designed to engage with the lacing at a 35 point near its other end, the distance between the first end and the clasp being sufficient to admit of forming a loose bow which effectively conceals the clasp.

My invention consists, further, of an improved fastening device one member of which 40 holds the end of the lacing against the tension imparted by the eyelets and the other member of which controls the position and direction of the said end of the lacing.

Referring to the accompanying drawings, Figure 1 gives a view of my improved lacing passed through the eyelets of a shoe, but with the fastening device unengaged and the bow unformed. Fig. 2 shows a partial view of the 45 lacing engaged with the fastening device with

a bow formed and sewed thereto, the bow and fastening device being seen from the rear. Fig. 3 shows a rear view of the improved fastening device which I prefer to use in connection with my lacing. Fig. 4 shows the fastening device seen in Fig. 3 in its flat form before having been bent into its final shape. Fig. 5 is an end view of the fastening device from the left hand in Fig. 3. Fig. 6 shows another form of fastening device which 50 may be used with my invention.

My invention in its simplest form, as shown in Fig. 1, consists of a lacing A of suitable length, to which is attached a clasp or fastening device B by stitches g, passing through 65 holes f in said fastening device, the latter being so positioned that the part of the lacing a' is of sufficient length to be formed into a bow or other ornamental knot, while the part a'' is of a length sufficient to pass through the 70 several lacing-eyelets of the shoe, engage the clasp or fastening device, and after so engaging to constitute one of the ends of the bow. If a lacing without "tags" or confining devices at the ends is used, the end a'' may be 75 trimmed after lacing to correspond in appearance to the end a' and may be subsequently trimmed as is rendered desirable by stretch of the lacing and by wear.

A desirable method of lacing a shoe with 80 my improved lacing is that shown in Fig. 1, which consists in first inserting the end of the lacing a'' in the upper eyelet e' and drawing it through said eyelet until the fastening device B is practically in contact with the eyelet. 85 The end of the lacing a'' is then passed successively through the eyelets e², e³, e⁴, e⁵, e⁶, e⁷, and e⁸. This method, however, is not a part of my invention and may be varied.

The form of fastening device which I have 90 shown in Figs. 1, 2, 3, 4, and 5 is die-drawn in the shape shown in Fig. 4 from a sheet of thin steel or other suitable metal. The holding member d is then bent upward, and the positioning member c is bent over till it nearly 95 touches the member d. The holes f, f having been punched, the whole is preferably tinned or nickel-plated.

In engaging the lacing with the clasp B the end a'' is first brought from beneath under the 100

member *d* and wedged between that member and the body part of the clasp by a gentle pull toward the left in Fig. 2. The end *a'* is then passed under the member *c* to impart to it the desired inclination as one of the ends of the bow.

In Fig. 2 a desirable form of my invention is shown, in which the end *a'* of the lacing is initially formed into a bow and permanently attached to the fastening device by the stitches *g*, passing through the holes *f*. The width of the center of the bow is preferably made sufficient that the edges of the bow can be drawn over and a little behind the edges of the fastening device to conceal the latter.

In Fig. 6 is shown another form of fastening device which can be used with my improved lacing. It consists of a plate of split sole-leather *h*, which can be sewed to the lacing and into which is riveted a device known in the art as the "Pratt fastener"—that is, a piece of spring-wire of helical middle section and ends bent downward at an angle of ninety degrees to serve as retaining devices to hold the fastening in the leather. The lacing is engaged with this fastening by inserting it between the turns of the wire *i*.

Having thus described my invention, I claim as new and desire to secure by Letters Patent of the United States—

1. A shoe-lacing having attached to it, at a

point intermediate of its length, a fastening device, the lacing on one side of the fastening device being adapted to form a bow, and the lacing on the other side of the fastening device being adapted to coöperate with the said fastening device, after passing through the eyelets of the shoe.

2. A shoe-lacing having at one end a bow and a fastening device, the other end being adapted to engage with the fastening device and become a part of the bow.

3. A shoe-lacing, one end of which is permanently formed into a bow, with a fastening device attached to said bow and adapted to engage with the lacing near its other end, after the lacing has passed through eyelets of the shoe.

4. In combination with a shoe-lacing, a fastening device, one member of which is adapted to engage and hold the lacing at a point near one of its ends, and the other member of which is adapted to support and position the end of the lacing which is secured by the first-mentioned member, for the purposes specified.

In testimony whereof I affix my signature in the presence of two witnesses.

HARRY W. PINKERTON.
